UNITED STATES PATENT OFFICE.

JOHN BAKER CROSSLEY, OF CLAY CENTRE, KANSAS.

NUT-LOCK.

SPECIFICATION forming part of Letters Patent No. 379,686, dated March 20, 1888.

Application filed June 23, 1887. Serial No. 242,781. (No model.)

To all whom it may concern:

Be it known that I, JOHN BAKER CROSSLEY, of Clay Centre, in the county of Clay and State of Kansas, have invented a new and Improved Railroad-Rail Tie, of which the following is a full, clear, and exact description.

My invention relates to an improvement in railroad-rail ties and has for its object to provide a safe tie, readily applied and used in connection with the ordinary fish-plates without changing the latter, and wherein the tie will be simple and cheap in construction, and readily removed by proper parties understanding its construction.

The invention consists in the construction and operation of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a side elevation of a section of rail having my improvement attached, and Fig. 2 is an end view of the same. Fig. 3 is a side elevation of the application of a modification, and Fig. 4 is an end view thereof. Fig. 5 is an enlarged side elevation of the applied tie, as illustrated in Fig. 1. Fig. 6 is a detail plan of the angle-plate employed, the tie-bar being in section; and Fig. 7 is a side elevation of the said tie-bar.

In carrying out the invention, an angle-plate, A, of thin metal, is employed, the length of which is about equal to the length of the fish-plate A', the vertical portion a being of a height nearly corresponding to the distance intervening the upper face of the rail-base and the under surface of the tread, and provided with four or more apertures, according to the number of bolts used in attaching the fish-plate.

The horizontal portion a' of angle-plate A is provided with a downwardly-extending longitudinal flange, b, integral with the outer edge, adapted to rest upon the upper surface of the rail-base at the outer edge, the said flange being of a width about equal to the angle of inclination of the said rail-base.

The horizontal portion of the plate A is recessed centrally of the outer edge, as at b', to admit of the usual spikes being made to en-

gage the abutting ends of the rails, as shown in Fig. 1, and centrally at each end of the said horizontal arm of the plate transverse elongated apertures b² are produced.

In the application the vertical portion of the plate is either made to intervene the fish-plate and the web of the rail, or made to abut against the outer surface of the fish-plate, preferably the latter, as shown in Figs. 1 and 5, being secured in position, in either case, by the usual bolts, c. A tie-bar, D, is now provided, made of either wood or metal, of a length equal to the length of the angle-plate. One end of the bar D, upon the under side, is fitted with a fixed stud, d, having a longitudinal lip, d', integral with the outer side, as shown in Fig. 7. The opposite end of the bar D, upon the under side, is provided with a transverse recess, e, and a vertical aperture leading into said recess. A pin, E, is made to slide in the aforesaid aperture, provided at the bottom with a lip, e', similar to the lip upon the stud, and a winged capped top, e², whereby the said pin is manipulated.

The angle-plate having been fixed as aforesaid, the stud d of the bar D is entered in one elongated aperture b², and the bar is then swung around parallel with the plate A, or the fish-plate, to a bearing upon the horizontal portion of the angle-plate and the under edge of the several fastening-bolts, the pin E having previously been raised upward to bring the lip e' into the recess e, to permit that end of the tie-bar passing readily upon the plate A.

To complete the attachment, the lip of the pin E having entered the registering aperture b², the said pin is turned so that the attached lip will engage one wall of the aforesaid aperture.

When the plate A is placed to the rear of the fish-plate it may be made of thinner material than when placed outside—such as sheet-iron or heavy tin. When thin metal is employed the flange b is omitted, and the metal instead is bent down at the ends longitudinally at right angles and in under the horizontal portion of the plate at an angle similar to the inclination of the rail-base, whereby the bearing h is found, as shown in Figs. 3 and 4.

Having thus described my invention, what I claim as new, and desire to secure by Letters Patent, is—

1. In a nut-lock, the combination, with a

railroad-rail and a fish-plate, of a second plate having its lower edge provided with a horizontal portion resting upon the rail-base, and the lock or tie bar interposed between the securing-bolt nuts and said horizontal portion of said second plate and detachably connected to said horizontal portion, substantially as and for the purpose set forth.

2. In a nut-lock, the combination, with a railroad-rail and the fish-plate, of an angle-plate having its vertical or main portion inter-

posed between the rail and the fish-plate, and its horizontal portion or arm resting upon the rail-base, and the lock or tie bar interposed between said horizontal portion or arm of the angle-plate and the securing-bolt nuts and detachably connected to said horizontal arm, substantially as and for the purpose set forth.

JOHN BAKER CROSSLEY.
